UNITED STATES PATENT OFFICE.

SAMUEL EUGENE BAKER, OF JOHNSTOWN, PENNSYLVANIA.

AMUSEMENT APPARATUS.

Application filed February 23, 1923. Serial No. 620,799.

To all whom it may concern:

Be it known that I, SAMUEL E. BAKER, a citizen of the United States, and a resident of Johnstown, in the county of Cambria and State of Pennsylvania, have invented a new and Improved Amusement Apparatus, of which the following is a full, clear, and exact description.

This invention relates to improvements in amusement apparatus, and has particular reference to a bowling game.

An object of the invention is to provide a game apparatus with which the same results may be obtained as in the ordinary game of tenpins or duck pins and wherein the use of pins and pin setters may be eliminated, thus reducing the operating cost to a minimum.

Another object is the provision of a plurality of members in the nature of targets having suitable counting characters thereon and which are movable across an alley to make it difficult to hit any particular one thereof with a ball.

25 A further object is to provide a signal which is automatically operated to indicate a successful hit when one of the targets is struck with a ball.

The above and other objects will appear more clearly from the following detail description, when taken in connection with the accompanying drawings, which illustrate a preferred embodiment of the inventive idea.

35 In the drawings—

Figure 1 is a transverse sectional view through a bowling alley showing the invention in front elevation;

Figure 2 is a section on the line 2—2 of Figure 1;

Figure 3 is a fragmentary plan view of the invention;

Figure 4 is a diagrammatic view illustrating the signalling apparatus employed in connection with the invention and the manner of its operation; and

Figure 5 is a detail perspective view of one of the targets.

Referring more particularly to the accompanying drawing, the numeral 6 indicates a bowling alley, which may be of standard construction and which is provided at one end thereof with a pit 7. The usual rack 8 having a portion 9 extending transversely across the rear end of the alley is also pro-

vided for returning the balls to the delivery end of the alley.

If desired, means may be provided for automatically returning the balls over the rack 8, in which event, the rear or lowermost end of the pit 7 is provided with a channel 10 into which the balls fall after being delivered into the pit and arranged above said channel is a housing 11 enclosing an endless conveyor 12 having a plurality of ball carriers 13 any one of which may receive a ball from the channel 10. The conveyor 12 is driven by a suitable motor 14 and operates to convey the balls upwardly from the channel 10 and deliver the same through an outlet 15 in the housing 11 onto the portion 9 of the rack 8, after which the ball will be returned over the rack in the usual manner.

The construction which comprises the essential features of the present invention includes a frame 16 of any suitable material which is suspended above the end of the alley adjacent the pit 7 by means of wires 17 or any other suitable suspending means. Supported at each end of the frame 16 are the large sprocket wheels 18, while intermediate the ends of the frame and adjacent the rear thereof a small driving sprocket 19 is provided. Also intermediate the ends of the frame and at the front thereof an idler sprocket 20 is provided and an endless conveyor chain 21 is passed around the several sprockets, as best illustrated in Figure 3. The sprocket 19 may be driven by a suitable motor 22 mounted on the frame 16 and operated from any suitable source of current supply.

Secured to and depending from the chain 21 is an endless strip 23 designed to support a plurality of targets 24, each of which is preferably made of leather or other relatively soft material and has a suitable counting character thereon, as shown in Figure 1. Each target 24 is of such length that the lower end thereof, when in operative position, will be disposed in the path of movement of either a tenpin or duck pin ball and is pivotally suspended by means of a frame 25, preferably formed of a single length of wire, the upper portion of which is secured to the strip 23 by means of clips 26.

The signal which is utilized to indicate to the player that a successful hit of a target has been accomplished, preferably includes a

lamp 27 carried by the frame at any suitable point and having one of its terminals connected to a battery 28 and its other terminal to a contact 29 carried by the frame 16. This contact is designed to engage a continuous conductor 30 secured to the inner surface of the strip 23 and fastened in position by means of the clips 26 which are also utilized to secure the frame 25 to said strip. The conductor 30 is electrically connected, through the clips 26 and each frame 25, to a contact 31 carried by each of the several targets 24 adjacent the upper ends thereof. The several contacts 31 are designed to engage a conductor 32 suitably carried by the frame 16 and extending across the front thereof. The conductor 32 is so disposed that when one of the targets 24, which happens to be moving across the front of the frame, is struck by a ball the upper end of the target will swing forwardly and the contact 31 thereon will engage with the conductor 32 and thus close the normally open circuit for the lamp 27, which will momentarily light to indicate to the player that one of the targets has been struck.

In order to make the targets 24 clearly visible, a plurality of lamps 33 may be carried by the frame beneath a reflector 34 which will aid in illuminating said targets.

In operation, the player will endeavor to time the delivery of his ball to hit the target marked "S" and if successful will then be entitled to a "strike" in his score. If, on his first ball, he should hit any of the other targets, as for instance target number 2, he will endeavor on his second ball to hit target number 8 in order to secure a "spare" in his score. The various targets 24 are spaced sufficiently apart to permit of a ball passing therebetween and if this should occur the player will be entitled to a score of "1". Following this procedure it will be apparent that the game may be played as in the ordinary bowling game.

What is claimed is:

1. The combination with a bowling alley; of an endless conveyor at one end of said alley and operable to move transversely thereof in a single horizontal plane, and a plurality of targets suspended from said conveyor.

2. The combination with a bowling alley; of an endless conveyor at one end of said alley and operable to move transversely

thereof, a plurality of targets pivotally connected to said conveyor and capable of being swung about their pivots when struck, a signal, and means contacted by said targets when struck for operating said signal. 55

3. The combination with a bowling alley; 60 of an endless conveyor at one end of said alley and operable to move transversely thereof, a plurality of targets suspended from said conveyor, a signal, and a normally open circuit for operating said signal including 65 a contact member capable of being engaged by said targets when the latter are struck by a ball to close said circuit.

4. The combination with a bowling alley; 70 of an endless conveyor at one end of said alley and operable to move transversely thereof in a single horizontal plane, and a plurality of targets pivotally connected to said conveyor in spaced relation to each other and arranged in the path of a ball moving on said 75 alley, the distance between adjacent targets being sufficient to permit said ball to pass therebetween.

5. The combination with a bowling alley; 80 of an endless chain movable transversely of said alley, a supporting strip carried by said chain, a plurality of frames suspended from said supporting strip, a target pivotally connected to each of said frames and arranged in position to be contacted by a ball moving 85 on said alley, and means actuated by a pivotal movement of one of said targets when engaged by a ball for indicating such engagement.

6. The combination with a bowling alley; 90 of an endless conveyor at one end of said alley and operable to move transversely thereof, a plurality of targets pivotally connected to said conveyor, a signal, and a normally open circuit for operating said signal 95 including a contact member arranged in the path of movement of said targets so as to be engaged thereby when the same are moved about their pivots.

7. The combination with a bowling alley; 100 of a plurality of targets movably suspended over said alley and in position to be contacted by a ball movable in said alley, a signal, and a normally open circuit for operating said signal including a contact member 105 engageable by said targets when the latter are moved by contact of a ball therewith.

SAMUEL EUGENE BAKER.
